UNITED STATES PATENT OFFICE.

EDWIN G. HATCH, OF NEW YORK, N. Y., ASSIGNOR TO CLARK ELECTRIC AND MANUFACTURING COMPANY, OF NEW YORK, N. Y., A CORPORATION OF NEW YORK.

INSULATOR-CLAMP.

1,190,763.

Specification of Letters Patent.

Patented July 11, 1916.

Application filed August 9, 1913. Serial No. 783,993.

To all whom it may concern:

Be it known that I, EDWIN G. HATCH, a citizen of the United States, and a resident of the borough of Brooklyn, county of 5 Kings, city and State of New York, have invented certain new and useful Improvements in Insulator-Clamps, of which the following is a specification accompanied by drawings.

10 This invention relates to insulator clamps for attaching an electric conductor to insulators, generally known as the pin type of insulator.

15 The objects of the invention are to protect the line conductor from mechanical or electrical injury at or in the vicinity of the insulator top.

20 Wherever electric power lines cross telephone or telegraph lines, there is generally danger to these latter systems in the event of the power conductor breaking, especially if this conductor be of a high tension, in which case its contact with the telephone or telegraph lines would make them most 25 dangerous, but injury may be caused to persons as well as damage to the line, causing interruption of service. It is also necessary that electric lines crossing railroad right of way shall be firmly attached to the insulators in order that the electric lines may 30 not break and possibly fall on the steel locomotive and thus become grounded and endanger the persons in the locomotive and the train.

35 An electric line is liable to break, due to either mechanical or electrical causes. The conductor may rub against the insulator top and so be gradually worn away. For this reason, it is desirable to clamp the conductor 40 tightly in place, preferably providing a bushing between the clamping members and the conductor itself. This bushing serves the further purpose of protecting the conductor against any slight electrical puncture through the insulator head and directly 45 below the conductor, because any arc formed will form from the bushing, rather than from the conductor itself. In case the short circuit through the insulator head should 50 be very severe and continued, so that the line wire fuses on the insulator head, then

the clamping members would still hold the line wire in position, because these members are ordinarily designed extra heavy and with large heat radiating surfaces.

55

One of the primary objects of this invention is to provide the insulator clamp with protective extension members extending longitudinally in the direction of the line wire or conductor. The extension members below the conductor extend in the general direction along the line and beyond the plane of the periphery of the insulator, but do not extend at right angles to the line, that is, across the insulator at right angles 60 to the line. These extension members below the line are provided to protect the conductor from the injurious effects of any arcs which may form to ground.

65

70 In the event of an electric surge in the transmission line or very high voltage caused by lightning or some other disturbing element, this voltage being higher than that for which the insulators have been supplied, an arc is very likely to jump to 75 ground and since the extension members on the clamp are lower than the line, the arc will form from the clamp to the ground, rather than from the line to the ground, so that the line is protected in this way. The 80 extension members may be formed of cheaper metal than the line, which is an economy.

75 Devices depending on cemented caps to hold them to the insulators have been discarded in many instances as being unsafe 85 and likely to work loose and it has been found much better to use clamps of suitable strength, which may be fastened to the insulator heads and which cannot work loose 90 therefrom. In accordance with this invention, these insulator clamps which clamp directly to the insulator are provided with the protective extension members. Although 95 the line is protected from arcs, no members are extended out at right angles to the line to extend beyond the insulators, because the use of these transverse extensions has been found not only to be unnecessary, but is in effect rather a menace than otherwise, as 100 inviting the formation of arcs which are likely to do damage. It has been found to

be much better to supply insulators having a high factor of safety, as regards electrical strength and thus protect the lines, rather than to have arcs form and take chances with them.

The invention is illustrated in some of its preferred forms in the accompanying drawings, in which—

Figure 1 is a side elevation of a clamp embodying the invention; Fig. 2 is an end elevation; Fig. 3 is a top plan view; Fig. 4 is a side elevation of a modification; Fig. 5 is an end elevation of a modification of Fig. 4; Fig. 6 is an end elevation of another modification; Fig. 7 is a detail side view of the protective plate shown in Fig. 6; Fig. 8 is a plan view of a modified form of plate; Fig. 9 is a top plan view of a modification of the clamp shown in Fig. 6; Fig. 10 is a side elevation of another modification; Fig. 11 is a top plan view of Fig. 10; Fig. 12 is a side elevation of another modification; Fig. 13 is a perspective view of another modification.

Referring to the drawings and more particularly to Figs. 1, 2 and 3, A represents an insulator shown in this instance as of the pin type, having the usual grooves B forming the neck of the insulator and a groove C diametrically crosses the top of the insulator for the reception of the line wire. The clamping members are shown in this instance provided with body portions D substantially encircling the insulator and jaws E for holding the line wire or conductor F. In this instance the line wire is inclosed within a suitable bushing G which may or may not be used, as desired. The jaws may be provided with clamping bolts H and J above and below the line wire, as shown in Figs. 1 and 2 or the upper bolts may be omitted, if desired.

As shown, the body portions D of the clamping members are provided with extension members K preferably forming an integral part of the clamps and extending outwardly longitudinally in the general direction of the length of the line wire and underneath said wire. These protective extension members K should also extend well beyond the plane of the periphery L of the insulator and serve to protect the conductor from the injurious effect of arcs which may form to ground. As shown, these extension members K are of substantial width at the base and taper toward the outer ends, which has been found to be a suitable construction, although the particular form of extension members may be varied, as desired. These extension members in effect form plates or wings directly underneath the line wire and extending along the length of the line wire adjacent the insulator clamps. Each wing or extension member is necessarily bifurcated,

since the two parts forming each wing are provided on the two body portions of the clamping members.

In Fig. 4 a construction substantially like that shown in Fig. 1 is illustrated with the addition of longitudinally extending protective members O connecting the jaws E'. These connecting protective members O further serve to protect the line wire from an arc caused by a possible grounding from above. This might be caused by the wet branch of a tree or a wire falling from above.

In Fig. 5 a modification of Fig. 4 is shown in which the connecting members O' are provided with outwardly extending extension members K'. These protective members K' do not extend beyond the periphery of the insulator, so that they do not invite the formation of arcs which might do damage, but merely increase the protection afforded by the longitudinal connecting members O'.

As an additional protection, it is frequently desirable to provide a portion or portions of the clamp of considerable thickness to cover all or a large part of the insulator top, the conductor being placed above this thickened portion, so that in the case of any puncture through the insulator head, the arc will form from this thickened portion of the clamp rather than from the line itself, thus protecting the line.

In Fig. 6 the protective cover for the insulator is shown at P and in detail in Fig. 7. This plate P may be provided with a diametrical rib or projection Q adapted to lie in the groove C of the insulator and is held down by the line wire F. Otherwise the construction of the clamp may be like that shown in the other figures. A modification of the plate P' is shown in Fig. 8, in which the plate is provided with notches Q' into which the jaws of the clamping members extend.

In Fig. 9 a modification of a construction is shown in which the plate R is formed as an integral part of one of the clamping members, secured directly to the jaws.

In Figs. 10 and 11 a modification is shown in which the jaw portions T of the clamping members are pivoted at U in any suitable manner to the body portions V. The clamping bolts U may in this instance form the pivots. These jaw portions T are provided with the extension members K' extending underneath the line wire and the jaw portions are also provided with the upwardly extending crossed extension members W, which serve to protect the line wire from above.

In Fig. 12 a modification is shown in which a third piece or plate X fits on top of the insulator between the insulator top and the conductor F and is provided with a

rib or projection extending into the groove on the top of the insulator. In this modification the protective plate X may be held in position as by means of the lugs Y through 5 which extend the bottom bolts J. Obviously various means may be provided for holding the protective plate in position.

In Fig. 13 another modification is shown in which a slightly different type of insulator clamp is provided with lower extension members. In this form of device, the curved body members a are held together by a bolt b at one end and are provided at the other end with a seat c against which clamps a 10 shoe d. The line wire F is held between the seat c and the shoe d. The body portions a of the clamping members are provided with the longitudinally extending members e which are bent downwardly and transversely 15 to extend underneath the line wire F. These extension members E also extend beyond the plane of the periphery g of the insulator and effect the same protection as afforded by the extension members K and K' in the other 20 figures.

Obviously the improvements herein disclosed relating to protective extension members and connecting members may be applied, not only to rigid clamps or clamps 25 having rigid clamping members, but may also be applied to insulator clamps in which the clamping jaws are pivoted to the body portions, as illustrated in Fig. 10 by way of example, and to clamping members which 30 are flexible instead of rigid, the clamping functions of both rigid and flexible clamps being the same.

I claim and desire to obtain by Letters Patent the following:

40 1. An insulator clamp comprising two clamping members having jaws clamping to the conductor and both having body portions encircling the insulator neck and adapted to be secured thereon, said body portions of 45 the clamping members both having separate and independent extension members connected directly thereto adjacent the said jaws and extending longitudinally of the conductor out of contact therewith beyond the periphery of the insulator.

50 2. An insulator clamp comprising two

clamping members having jaws clamping to the conductor and both having body portions encircling the insulator neck and adapted to be secured thereon, said body portions 55 of the clamping members both having separate and independent extension members extending outwardly beyond the periphery of the insulator longitudinally below the conductor and out of contact therewith, to 60 protect the conductor from the injurious effects of arcs which may form to ground.

3. An insulator clamp comprising two clamping members having body portions and jaws, said jaws clamping to the conductor, 65 and the body portions encircling the insulator neck and adapted to be secured thereon, said body portions both being provided with separate and independent extension members, extending longitudinally below the conductor out of contact therewith and beyond 70 the insulator to which the clamp is secured, to protect the conductor from the injurious effects of arcs which may form to ground.

4. An insulator clamp comprising two 75 clamping members clamping to the conductor and both encircling the insulator neck and adapted to be secured thereon, said clamping members both having extension members extending longitudinally above 80 and below the conductor, the lower extension members projecting beyond the insulator to protect the conductor from the injurious effects of arcs which may form to ground.

85 5. An insulator clamp comprising two clamping members both encircling the insulator neck and adapted to be secured thereon and having jaws for clamping to the conductor, connecting members connecting the 90 jaws above the conductor, and extension members connected directly to both of the clamping members and extending longitudinally below the conductor beyond the plane of the periphery of the insulator.

95 In testimony whereof I have signed this specification in the presence of two subscribing witnesses.

EDWIN G. HATCH.
